UNITED STATES PATENT OFFICE.

LOUIS SEVERUS, OF CHICAGO, ILLINOIS, ASSIGNOR TO ART LAMP MANUFACTURING COMPANY, OF CHICAGO, ILLINOIS.

DESIGN FOR A PENDULET.

Application filed January 5, 1925. Serial No. 11,899. Term of patent 3½ years.

To all whom it may concern:

Be it known that I, LOUIS SEVERUS, a citizen of the United States, residing at Chicago, in the county of Cook and State of Illinois, have invented a new, original, and ornamental Design for a Pendulet, of which the following is a specification, reference being had to the accompanying drawings, forming part thereof.

The figure is a view in elevation showing my new, original and ornamental design for a pendulet.

I claim:

The ornamental design for a pendulet as shown.

LOUIS SEVERUS.
